UNITED STATES PATENT OFFICE

2,682,695

CONCRETE TILE FORMING MACHINE

Neuman E. Ramsey, Kansas City, Mo.

Application November 16, 1950, Serial No. 196,000

6 Claims. (Cl. 25—36)

1

This invention relates to automatic machines for producing tubular members from cementitious materials and has to do more specifically with concrete forming apparatus capable of intermittently feeding the material into tubular molds therefor as the latter are continually and successively moved into and out of a feeding position.

Machines of the kind forming the subject matter of this invention have heretofore been developed and placed in use but for the most part, the same are not entirely automatic and therefore, require a number of workmen, together with constant attention in order to form concrete tiles with any degree of speed. Oftentimes such machines also require an additional workman for feeding the material into the molds, together with another worker for intermittently shifting the molds into a feeding position as still another workman removes the molds from the machine and replaces the same after the tile has been removed therefrom.

It is the most important object of this invention therefore, to provide a concrete tile forming machine that includes a turntable operably connected with other parts of the machine for supporting a plurality of forms and shifting an empty form into a feeding position during each cycle of operation.

Another object of this invention is to provide a tile forming machine that includes a reciprocable forming and packing plunger, the aforesaid turntable being operated by the same mechanism that is provided to cause reciprocation of the plunger.

Another equally important object of the invention is to provide means in a tile forming machine to automatically hold the aforesaid plunger against movement at one end of its path of travel momentarily while the same is in the mold so that sufficient time is allowed to direct cementitious material thereinto and thereby present a fully formed and adequately packed tile throughout the length thereof and particularly at its lowermost end.

Other objects of this invention include the way in which the feeding device is rendered operable only when the forming and packing plunger is within the tubular mold; the way in which the speed of operation of the entire assembly may be easily and quickly adjusted without the necessity of resynchronization; the manner of locking the mold being filled in position on the turntable each time the same moves to a feeding position; the way in which the turntable is stepped 90° during each cycle of operation and locked against move-

2

ment while the tile is being formed; and the manner of preventing reciprocable movement of the tile locking means while the same is in a position holding the tile in place on the turntable.

5 Many more minor objects including details of construction and novel arrangement of parts will be made clear or become apparent as the following specification progresses, reference being had to the accompanying drawings, wherein:

10 Figure 1 is a side elevational view of a concrete tile forming machine made pursuant to my present invention.

Fig. 2 is a front elevational view thereof.

Fig. 3 is a fragmentary, rear elevational view, 15 parts being broken away to reveal details of construction.

Fig. 4 is a transverse, cross-sectional view taken on irregular line IV—IV of Fig. 1, looking in the direction of the arrows.

20 Fig. 5 is a transverse, cross-sectional view taken on line V—V of Fig. 3.

Fig. 6 is a transverse, cross-sectional view taken on line VI—VI of Fig. 3.

Fig. 7 is a fragmentary, sectional view showing a portion of one side of the machine opposite to that illustrated in Fig. 1 of the drawings and taken on line VII—VII of Fig. 2.

Fig. 8 is a fragmentary, detailed, cross-sectional view taken on line VIII—VIII of Fig. 1.

Fig. 9 is a fragmentary, detailed sectional view 30 taken on line IX—IX of Fig. 2; and

Fig. 10 is a fragmentary, elevational view opposite to that illustrated in Fig. 2 and showing a portion of the structure illustrated in Fig. 7.

35 The entire machine forming the subject matter hereof and illustrated in the drawings may be suitably supported in any desired manner on a base not shown, upon which base is mounted an elongated, vertical primary frame member 10 that is H-shaped in cross-section as illustrated in Figs. 4, 5 and 6 of the drawings.

40 A horizontal spider-like turntable 12, provided with a central opening (not shown) circumscribes the upright frame member 10 intermediate the ends of the latter and is supported for rotation about the vertical axis of frame member 10 by a plurality of rollers 14 carried by standard 10 on the outer faces thereof. The turntable 12 as illustrated, includes four fingers, each adapted to receive and support a tubular mold 16 of conventional character in that the same is split longitudinally and provided with a lock not shown for releasably holding the same in a tubular condition until such time as the tile formed therein is to be released.

Both ends of the form 16 are open and when the same is supported in an upright condition by the turntable 12, the lowermost end thereof fits within a circular opening 18 formed within each finger respectively of the turntable 12. The lower end of the form 16 rests upon an annulus 20 underlying the turntable 12 and affixed thereto in concentric relationship to the corresponding opening 18.

A pair of opposed, L-shaped lugs 22 (Fig. 1), adjacent each opening 18 respectively, receive opposed pins 24 on the forms 16 near the lowermost end of the latter to hold the same in place. The pins 24 are moved into and out of a position locked with the lugs 22 by merely rotating the form 16 on its longitudinal vertical axis. The turntable 12 is rotated in the direction indicated by the arrow in Fig. 4 intermittently 90° in step-by-step fashion through mechanism hereinafter to be described successively bringing the molds 16 into a feeding position underlying a cup-shaped, horizontal feed table 26.

Table 26 is illustrated in Figs. 1, 2 and 7 of the drawings at the lowermost end of its reciprocable path of travel as is a forming and packing plunger 28 as the same would appear if a form 16 were in position interposed between table 26 and the turntable 12. For clearness however, such form 16 to be fed with cementitious material is not shown in the feeding position in Figs. 1 and 2. The feed table 26 is connected rigidly to a pair of opposed vertically reciprocable rods 30 and 32 through the medium of a pair of laterally extending arms 34 and 36 respectively. The vertically reciprocable, elongated rods 32 are carried by the upright 18 on opposite faces thereof by spaced bearings 38, the lowermost bearings 38 serving as stops for limiting the extent of downward movement of the rods 30 and 32 and the feed table 26 with its arms 34 and 36.

The plunger 28 is mounted on the lowermost end of an elongated stem 40 that is both rotatable and reciprocable on its longitudinal vertical axis. The stem 40 extends upwardly through a central opening 42 formed in the bottom of feed table 26 and having a diameter sufficiently large to receive and clear the plunger 28. Rotation of the stem 40 and of the plunger 28 thereon is effected through the medium of an electric motor or other prime mover 44 suitably carried by the standard 18 near the uppermost end of the latter, having connection with a pulley 46 through endless belts or the like 48. The pulley 46 is mounted upon the stem 40 through the medium of a plurality of vertical grooves 50 formed in the stem 40, there being lugs in the pulley 46 slideable within the grooves 50 as the stem 40 is caused to reciprocate vertically. In other words, the connection between pulley 46 and the stem 40 is of conventional character permitting pulley 46 to rotate the stem 40 and at the same time permitting the stem 40 to reciprocate upon its longitudinal axis within the pulley 46 as continuous rotation takes place.

The standard 18 has a pair of opposed tracks 52 carried on opposite faces thereof and to one side of the rods 30 and 32 respectively for guiding a pair of opposed vertically reciprocable identical plates 54. The plates 54 extend outwardly from the tracks 52 beyond the standard 18 and converge as the outermost ends thereof are approached.

The plates 54 are joined by a bottom wall 56 that extends outwardly beyond plates 54 and rotatably receive the stem 40 together with a block 58 on wall 56. While the stem 40 is rotat-

able within wall 56 and block 58, it cannot reciprocate relative thereto. A plurality of opposed rollers 60 for each of the tracks 52 respectively, guide the plates 54 and structure carried thereby including stem 40 as the same reciprocate vertically along tracks 52.

The plates 54 are also joined by a cross-bar 62 that is in turn connected with a stem 64 forming a part of an hydraulic system through the medium of a bracket 66. Stem 64 joins at that end thereof opposite to bracket 66 with a piston 68 mounted within a vertically disposed cylinder 70 carried within a portion of the standard 18. It is seen therefore, that as hydraulic pressure is directed to the cylinder 70 on either side of the piston 68, the stem 64 will be reciprocated to impart the same motion to plates 54 and the stem 40 of plunger 28.

The reciprocable rods 30 and 32 are each normally locked against upward movement whereby to hold the feed table 26 in the position illustrated in Figs. 1 and 2 through the medium of toggle mechanism including a link 72 pivotally interconnecting standard 18 at the uppermost end thereof and a cam member 74 that is pivotally secured to the uppermost end of the corresponding rod 32. The two locks are "broken" by upward movement of the plates 54 through the medium of a small roller 76 on each plate 54 respectively that contacts the cam member 74. As the rollers 76 continue to move upwardly under the influence of the piston stem 64, and after the cam member 74 have been swung on their pivot points, the rollers 76 move into a cam-like notch 78 formed in the cam member 74 carrying therewith the rods 30 and 32 and causing the same to move from the position illustrated in Figs. 1 and 2 to an elevated position not shown. Obviously, as rods 32 rise in this fashion, the feeding table 26 will be carried therewith and move upwardly away from the turntable 12.

The feed table 26 is formed similarly to the turntable 12 in that the opening 42 thereof has an annulus 80 for receiving the uppermost end of the form 16 and holding the same on the turntable 12 when the feed table 26 is in the position illustrated in Fig. 1. Accordingly, as the table 26 moves upwardly, the forms 16 are free to rotate under influence of the turntable 12 and as the table 26 returns to its lowermost position, an empty form 16 is engaged thereby and held locked on the turntable 12.

It is further understood that when the stem 64 moves downwardly to cause descent of roller 76, the latter will actuate cam member 74 to again lock the rods 30 and 32 and the feed table 26 against upward movement.

The means for imparting rotation to the turntable 12 all through prime mover 44, is illustrated in Figs. 3, 5 and 6 and includes a spring-loaded swingable dog 82 on the turntable 12 for each finger thereof respectively that is engaged by a latch member 84 swingably secured to the standard 18. Swinging movement is imparted to the latch member 84 each time the piston stem 64 rises, by means of a cross-bar 86 that joins the rods 30 and 32 adjacent the arms 36 of table 26.

An extensible bar 88 pivotally connected with the cross-bar 86 intermediate the ends thereof has pivotal connection at its lowermost end with a link 90 swingably secured to the standard 18. A bell crank 92 pivoted on a horizontal axis 94 has one of its arms pivotally connected with the link 90 by a short link 96, and its other arm piv-

totally joined with a reciprocable bar 98 by means of a short link 100. Swinging movement is imparted to the latch member 84 therefore, upon reciprocation of bar 98 through the medium of a link 102 that pivotally interconnects bar 98 and the latch member 84.

The hydraulic system above mentioned and forming a part of the machine hereof is for the most part quite conventional and has therefore, not been detailed. However, for reasons herein-after to be made clear, it is advantageous to drive the hydraulic pump 104 thereof directly from the continuously rotating stem 40 through the medium of an endless belt 105. The system including pump 104 couples directly with a two-way valve 106 mounted on a plate 108 carried by upright 10 by means of line 110. Valve 106 is provided with two outlet pipes 112 and 114 joined with the uppermost and lowermost ends respectively of cylinder 70 and a relatively small receptacle 116 joins with the pipe 114 by conduit 118.

Cementitious material to be fed into a form 16 within a feeding position below table 26 is stored within a hopper-like bin 120 provided with an outlet opening at its lowermost end not shown, directly overlying an inclined chute 122. There is provided within the bin 120 an auger, not shown, for feeding the material into the trough or chute 122 that is driven by a prime mover 124 connected directly with the auger through suitable gear reduction by means of an endless belt or the like 126.

The shaft 128 for the aforesaid auger has a link 130 clamped thereto that is in turn pivotally connected with an elongated arm 132. Arm 132 swings a link 134 to which it is pivotally connected that is joined with agitating means in hopper 120 capable of scraping certain of the walls of the hopper 120 and causing the cementitious material to flow downwardly to the trough 122.

Trough 122 is swingably joined with a frame 136 that supports hopper 120 by means of a pin 138 extending through a loop 140 depending from and rigid to the trough 122. The lowermost end of trough 122 is carried by the feed table 26 through the medium of a pin 142 carried by the latter and a short shaft 144 underlying the trough 122 and pivoted to the uppermost end of pin 142.

The conventional two-way valve 106 is operated through reciprocation of rod 30 in the manner illustrated in Fig. 7. A pair of oscillatory triggers 146 and 148 are carried by the plate 108, trigger 148 being connected directly to the valve 106 and being actuated by the swingable trigger 146 through the medium of a pair of spaced stops 150. An arm 152 swingable on the plate 108 is provided with a roller 154 intermediate the ends thereof, yieldably held biased against the trigger 146 by a spring 156. Connecting member 158 on the trigger 146 is slidable on an elongated vertical rod 160 between a pair of stops 162 on rod 160. Rod 160 is carried for vertical reciprocation by a pair of bearings 164 on standard 10. The lowermost end of the rod 160 is in direct alignment with crossbar 86 and a lateral projection 166 aligns with a bracket 168 on one of the plates 54 supporting its roller 76.

The plunger 28 is formed as illustrated in Figs. 1, 2 and 8 to operate both as a forming means and as a packer and includes a cylindrical, preferably solid, lowermost portion 170 and an upper portion that comprises a pair of opposed

segments 172 presenting a pair of opposed spaces therebetween and above the solid portion 170.

Laterally projecting notched plates 174 are mounted at the outermost end of each finger respectively of the turntable 12 for receiving a locking bar 176 depending from the feed table 26 whereby to hold the turntable 12 against rotation when the feed table 26 is at the lowermost end of its path of travel as shown in Figs. 1 and 2.

During operation, prime mover 44 is energized continuously to rotate the stem 40, the plunger 28 carried thereby and to actuate the pump 104 of the hydraulic system. Hydraulic fluid will immediately be directed toward the lowermost end of cylinder 70, but the least resistance to such flow of fluid is into the receptacle 116 by way of conduit 118. Consequently, for a moment, the piston 68 will not be driven upwardly within the cylinder 70 and accordingly, the plunger 28 will not rise from the position illustrated in Figs. 1 and 2 until such time as the receptacle 116 becomes filled with fluid. It is assumed of course, that all four fingers of the turntable 12 support a form 16 and that prior to downward movement of the plunger 28, one of such forms 16 is in a position directly underlying the table 26 and aligned with the opening 42 thereof. When all of the parts are in the condition illustrated in Figs. 1 and 2, one of the rollers 76 bears against an arm 178 of an electric switch for energizing the prime mover 124 and thereby feed cementitious material from hopper 120 to the chute or trough 122. Such material flows upon the feed table 26 and thence through opening 42 and into the form 16 around the combination packer and forming plunger 28. As soon as piston 68 rises, plunger 28 moves upwardly within the mold 16 to form the tubular tile member and pack the cementitious material tightly against the inner walls of the mold 16. Such movement of plunger 28 is effected by virtue of the connection 66 of stem 64 and the plates 54 which are in turn joined with the rotating stem 40 of plunger 28.

As soon as one roller 76 that engages arm 178, moves to a position opening the switch for motor 124, the material ceases to flow from the hopper 120. After the rollers 76 move to a position engaging the cam members 74, the rods 30 and 32 are unlocked and caused to move upwardly with and by the rollers 76. This action raises the table 26 away from its contacting relationship with the form 16 and simultaneously moves the bar 176 out of engagement with the proximal plate 174, thereby releasing the turntable 12 for rotational movement. The two-way valve 106 remains in a position permitting flow of hydraulic fluid to the lowermost end of the cylinder 70 until such time as the table 26 and the cross-bar 86 commence to rise and until such time as the cross-bar 86 comes into contact with the lowermost end of rod 160. As rod 160 rises, the lowermost stop 162 comes into contact with connector 158 to swing the trigger 146 against the action of spring 156 to a point below roller 154. As soon as the lowermost stop 150 of trigger 146 contacts the trigger 148, the latter will be swung and the valve 106 actuated.

The flow of hydraulic fluid immediately changes to drive the piston 68 downwardly and to permit return flow of fluid therebelow to the pump 104. Valve 106 is again actuated on downward movement of the plates 54 by virtue of bracket 168 contacting extension 166. Here

again, delayed action takes places since the trigger 146 is not actuated until the upper stop 162 contacts the connector 158 and the trigger 148 is not actuated until the uppermost stop 150 of trigger 146 comes into contact with trigger 148.

Simultaneously, with the aforesaid upward movements of stem 40 and feed table 26, cross-bar 86 operates to step the turntable 12—90° for moving a mold 16 having a formed tile therein from beneath table 26 and for positioning an empty mold 16 in a feeding position. Upward movement of cross-bar 86 imparts like movement to connector 86 swinging link 90 and causing bell crank 92 to rotate on its pivot 94 by means of link 96. When bell crank 92 swings, it reciprocates the bar 98 to cause swinging movement in latch 84 through link 102. The latch 84 engages the proximal dog 82 which shifts the table 12 as aforesaid. On downward movement of the cross-bar 86, the action just described is reversed, the latch 84 returning to a position for receiving the spring-loaded dog 82.

It is seen therefore, from the foregoing that the machine is entirely automatic and that the only workman that is necessary is one to remove the tubular form 16 from the turntable 12 after a tile has been formed therein and to replace the same with an empty form 16. It will be recalled that the forms 16 are of a split nature and provided with a lock which is released after the tile is formed for removing the latter and conditioning the form 16 for further use. The diameter of the plunger 28 is of course, less than the inside diameter of forms 16 and accordingly, the tile formed thereby will have an inside diameter equal to that of the plunger 28.

The importance of the delayed action of plunger 28 at the lowermost end of its path of travel, is worthy of repetition since in the absence of such construction, tiles formed through use of a machine of this character will not be adequately filled and packed at one end thereof. By permitting plunger 28 to rotate without reciprocation within the form 16, a sufficient amount of cementitious material will be directed into the form and packed against the inner walls thereof to present a completely filled and relatively strong tile structure throughout the length thereof.

Having thus described the invention what is claimed as new and desired to be secured by Letters Patent is:

1. In a tile making machine, a hydraulic cylinder having a vertically reciprocable piston provided with a stem extending upwardly from the cylinder; an elongated, upright rod in spaced parallelism to said stem; structure connecting the stem with the rod for reciprocation therewith, said rod being rotatable on its longitudinal, vertical axis; a prime mover operably coupled with the rod for rotating the latter as the same reciprocates; a forming and packing plunger on the rod at the lowermost end thereof; guide means spaced from the rod and the stem; means mounting the guide means for vertical reciprocation; a feed table surrounding the rod above the plunger; means for supporting a tile form below the table in alignment with the plunger, said table being secured to the guide means for reciprocation therewith to and from a position resting on said tile form; a lock for holding the guide means at the lowermost end of its path of travel, said lock having a cam member swingable on the guide means to and from a position releasing the latter for upward movement; and an

extension on said structure engageable with said cam member as the stem moves toward the uppermost end of its path of travel, said cam member having a notch for receiving the extension after release of the cam member and upon continued upward movement of the stem whereby the guide means is raised and the table is lifted as the stem moves to said uppermost end of its path of travel.

2. In a tile making machine as set forth in claim 1 wherein said extension is spaced below the cam member when the table is on the tile and the rod is at the lowermost end of its path of travel whereby to delay raising of the table until the plunger has risen a predetermined distance above the lowermost end of its path of travel.

3. In a tile making machine as set forth in claim 1, wherein said tile form supporting means is rotatable about said vertical axis of the piston, and wherein is provided stepping mechanism operably coupled with said supporting means for rotating the latter, and means interconnecting the stepping mechanism and the guide means for actuating the mechanism upon reciprocation of the guide means.

4. In a tile making machine as set forth in claim 1, wherein is provided means for pumping hydraulic fluid, a movable valve for directing said fluid to the cylinder below the piston when the valve is in one position and to the cylinder above the piston when the valve is in a second position, means on said structure for moving the valve to said one position as the stem descends, and means on said table for moving the valve to said second position as the stem rises.

5. In a tile making machine as set forth in claim 1, wherein is provided means for pumping hydraulic fluid, a movable valve for directing said fluid to the cylinder below the piston when the valve is in one position and to the cylinder above the piston when the valve is in a second position, valve actuating mechanism including a vertically reciprocable element and a swingable connector, said connector being operably coupled with the valve, means on said structure for lowering said element as the stem descends, means on said table for raising said element as the stem rises, a stop on the element engageable with the connector to move the valve to said one position as the element is lowered, and a stop on the element engageable with the connector to move the valve to said second position as the element is raised.

6. In a tile making machine as set forth in claim 5, wherein said stops are spaced on the element with the connector disposed therebetween whereby to delay movement of the valve alternately to said positions thereof as the stem reciprocates.
